Primary Examiner — Martie K Holtje(74) *Attorney, Agent, or Firm* — Stetina Brunda Garred & Brucker(57) **CLAIM**

The ornamental design for a pet leash with storage pouch, as shown and described.

DESCRIPTION

FIG. 1 is an upper perspective view of the pet leash with storage pouch of the present invention showing the new design;

FIG. 2 is a lower perspective view thereof;

FIG. 3 is a top plan view thereof;

FIG. 4 is a front elevational view thereof;

FIG. 5 is a bottom plan view thereof;

FIG. 6 is a rear elevational view thereof; and

FIG. 7 is an end elevational view thereof; and,

FIG. 8 is an end elevational view opposite to the end depicted in FIG. 7.

The hardware and zipper pulls depicted by broken lines in the drawings have been shown for the purpose of illustrating portions of the pet leash with storage pouch that form no part of the claimed design.
